UNITED STATES PATENT OFFICE.

JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

APPARATUS FOR FORMING AND FLANGING CAN-BODIES.

1,315,114.

Specification of Letters Patent. Patented Sept. 2, 1919.

Application filed September 8, 1916. Serial No. 119,065.

To all whom it may concern:

Be it known that I, JAMES A. GRAY, a citizen of the United States, residing at the city and county of San Francisco and State of California, have invented certain new and useful Improvements in Apparatus for Forming and Flanging Can-Bodies, of which the following is a specification.

The present invention relates to can making machinery, and more particularly to an apparatus for restoring can bodies to their original cylindrical shape after they have been flattened, as for the purpose of shipment or storage, and for forming flanges on the ends of said can bodies.

As is well known in the art, the bodies of cans designed to be used for the preservation of food products or other material, are frequently flattened by compressing opposite sides, in order that they may occupy less space during shipment and storage. It is necessary, therefore, to restore these flattened can bodies to their original shape before applying the first end or bottom thereto.

The object of the present invention is to provide a machine which may be used by a packer who has received and stored his supply of cans in flattened form, for reforming said cans and forming the necessary flanges on the ends thereof for having applied thereto flanged ends.

In order to comprehend the invention, reference should be had to the accompanying sheets of drawings, wherein:

Figure 1 is a side elevation of the complete machine.

Fig. 2 is a sectional plan view looking in the direction of the arrows on the line 2—2 of Fig. 1.

Fig. 3 is a part sectional end elevation of the machine, certain parts being omitted for the sake of clearness.

Fig. 4 is a vertical section through the feed mechanism, taken on line 4—4 of Fig. 2 and viewed in the direction of the arrows.

Fig. 5 is a longitudinal sectional detail taken on the line 5—5 of Fig. 3 and viewed in the direction of the arrows, showing the flanging mechanism.

In the drawings the reference numeral 1 designates any suitably constructed base or bed-plate, which is preferably supported upon legs 2, as illustrated in Fig. 1 of the drawings particularly.

Mounted upon the bed-plate 1 is a superstructure 3, in which is journaled a horizontal transverse drive shaft 4, Figs. 1 and 2 of the drawings. This shaft 4 constitutes the main driving means for the entire machine, and is shown as carrying a belt-pulley 5 at one end, by means of which said shaft may be driven.

A mutilated worm 6, Fig. 2 of the drawings, fixed upon the drive shaft 4, and meshing with a worm-wheel 7 mounted upon a shaft 8, disposed at right angles to the drive-shaft 4, imparts an intermittent rotary movement to said shaft 8. The shaft 8 is journaled in a superstructure 9, which is supported by the previously mentioned superstructure 3. A turret 10, in the present case mounted in a plane for vertical rotation, is secured upon one end of the shaft 8, and at regular intervals about this turret 10, near the periphery thereof, is a series of fixed outwardly projecting studs 11. Mounted for free rotation upon each stud 11 is a cylindrical mandrel 12, preferably formed as shown in the drawings with a tapering or conical end portion 12'. Suitable means are employed for retaining the mandrels 12 upon their respective studs 11, said means being shown in the drawings as comprising a screw 13 secured to the free end of each stud 11.

Another horizontal shaft 14, Figs. 1, 2 and 3 of the drawings, parallel to the shaft 8, and below and to one side thereof, is journaled in brackets 17 and 18 mounted upon the bed plate 1, and is continuously driven by the drive-shaft 4 through suitable bevel gears 15 and 16. A yoke 19, Figs. 1 and 3 of the drawings, is pivoted at one end concentric with the shaft 14 and in its outer end carries a short rotatably mounted shaft 21, said shaft 21 being driven by the shaft 14 through suitable spur gears 22 and 23, and carrying an ironing or reforming roller 20, positioned parallel to and adapted for contact with the cylindrical portions of the mandrels 12, when said mandrels are successively brought into position by the intermittent rotation of the turret 10. Contact between the roller 20 and the positioned mandrel 12 is preferably secured by means of a plate 24, Figs. 3 and 5 of the drawings, slidably mounted upon studs 25 fixed to the under side of the bed-plate 2, said plate 24 being pressed upwardly by springs 26, and sup-

porting the free end of the yoke 19 by means of the pins 27 interposed therebetween.

A magazine 30^a for containing a supply of flattened can bodies is supported upon the bed-plate 1 by means of two spaced vertically disposed bracket members 28, Figs. 1, 2 and 3 of the drawings, which support, by means of angle brackets 29, Fig. 1, an inner pair of spaced vertical plates 30, Figs. 1, 2 and 4, having angle members 31 fixed to their edges, said plates 30 and angle members 31 forming a vertical magazine for the reception of a stack of flattened can bodies 32.

Immediately beneath the magazine thus formed is a horizontal guide plate 34, Figs. 1, 2, 3 and 4 of the drawings, in the guide ways 36 of which is carried a sliding member 35. Horizontal reciprocating motion may be imparted to the slide 35 by any convenient means the same comprising, in the present instance, a lug 37, Figs. 1 and 4 of the drawings, on the under side of said slide 35, a lever 38 connected to said lug 37 by means of a link 39, said lever 38 being fulcrumed at 40' to a bracket 40 extending from one of the legs 2 of the machine, and being connected by a pitman rod 41 to an eccentric strap 42 which surrounds an eccentric 43 fixed upon the drive shaft 4.

The slide 35 carries an upwardly extending lug 44, Fig. 4 of the drawings, to which is fixed two forwardly extending fingers 45 adapted to engage the lowermost can body 33 of the stack of can bodies 32 contained within the magazine 30^a and to push said lowermost can body out of said magazine and on to spaced guide members 46 adjacent thereto, each of said guide members 46 being carried by a pair of swinging spreader arms 47. Said swinging spreader arms 47, Figs. 1, 2 and 3 of the drawings are mounted in pairs upon each side of the magazine supporting brackets 28, and have inwardly projecting lower ends 48 formed with notches 49, adapted to engage the can body 33 when dropped, as hereinafter described, from its position upon the guide members 46, and by laterally compressing said can body, to spread or expand it preliminarily. Said pairs of arms 47 are mounted upon spaced horizontal shafts 50 and 51, the shaft 51 being extended, as shown in Fig. 1 of the drawings, through a journal bracket 52, and carrying on its end a lever-arm 53, Figs. 1 and 3 of the drawings, said lever-arm being connected by a vertically disposed pitman rod 54 with a yoke 55 embracing the drive-shaft 4, and carrying a cam-following roller 56, adapted to lie within and follow the groove 57 of a cam member 58, secured upon the drive-shaft. Oscillatory motion is thus imparted to the shaft 51, and is transmitted to the shaft 50 by means of a bar 59, connecting levers 60 and 61, extending in opposite di-

rections from the shafts 50 and 51 respectively. Thus the opposite pairs of swinging arms 47 are caused to swing in and out simultaneously and in opposite directions.

The outward movement of the swinging spreader-arms 47 causes a separation of the guide members 46, thereby permitting the can-body 33 to drop into the notches 49 of said spreader arms. The subsequent inward movement of said arms compresses said can body laterally and thereby spreads the same by an amount sufficient to permit the entrance thereinto of a pair of spaced spreader rods 62, Figs. 1, 2 and 4 of the drawings and a spreader horn 63 positioned between said spreader rods 62, said rods and said horn being carried by, and projecting forwardly from, the lug 44 of the slide member 35. Said slide also carries a pair of spaced forwardly extending fingers 64, positioned below and extending beyond the spreader horn 63, as shown in Figs. 3 and 4 of the drawings, for engaging the end of a partially opened can body 33' and forcing the same onto a mandrel 12 positioned in proper alignment therewith.

An apertured guide-plate 65, against which the preliminary spread can body 33 abuts, retains said can body in position during the entrance thereinto of the spreader rods 62 and the spreader horn 63.

Thus it will be seen, by reference to Figs. 2, 3 and 4 of the drawings, that in the present case three complete strokes of the slide member 35 are required to transfer a flattened can body from the magazine 30^a to a positioned mandrel 12. The first inward stroke of said slide removes the lowermost can body 33 from the magazine by means of the pusher fingers 45, and pushes the same upon the guide members 46 carried by the swinging arms 47, Figs. 1 and 4 of the drawings. During the return movement of the slide 35 said swinging arms are separated and brought together as previously described, to permit said can body 33 to drop into the notches 49 and to be laterally compressed thereby, and preliminarily opened. The second inward stroke of the slide 35 causes the introduction into the preliminarily opened can body 33 of the spreader rods 62 and the spreader horn 63, thereby further expanding and spreading said can body. At the same time the succeeding flattened can-body is removed from the magazine by the pusher fingers 45, and positioned upon the guide members 46. The third inward stroke of the slide 35 causes the fingers 64 to push the partially spread can body 33' which has been released by the outward movement of the arms 47 from the notches 49 thereof, and dropped into the position shown in Fig. 3, and is then pushed on to the aligned mandrel 12. At the same time the second can body 33 which has

been preliminarily opened by the swinging arms 47, is further opened by the spreader rods and spreader horn, and the third flattened can body is removed from the magazine by the pusher fingers 45, and positioned upon the guide members 46.

The can body 33', positioned upon the mandrel 12 at the position "A", Fig. 3 of the drawings, is then carried by the intermittent rotation of the turret 10 to the position B, at which position it is not acted upon. The next movement of the said turret carries said can body 33' to the position C, where it is ironed and restored to its cylindrical form by contact with the revolving ironing roller 20. The following movement of the turret 10 carries the reformed can body to the position D, at which the flanging operation takes place.

This flanging is accomplished by the following mechanism: The mandrel 12 is formed near its inner end, as shown in Figs. 2 and 5 of the drawings, with a portion 66 of enlarged diameter, the diameter thereof being that of the interior of the reformed can body. A shoulder 67, having formed therein a flanging groove 68, is formed upon the mandrel 12 adjacent to and behind said enlarged portion 66. A reciprocating flanging die 69, adapted to be introduced over the end of the mandrel 12, has at its free end an annular portion 70 of a diameter sufficient to enable it to enter the end of the reformed can body 33'. A shoulder 71, having formed therein a flanging groove 72, is formed upon said die 69 immediately back of the portion 70. Thus by forcing the die 69 over the end of the mandrel 12 and against the end of the can body 33', carried thereby, the ends of said can body are forced over the enlarged portions 66 and 70 of the mandrel 12 and the die 69 respectively, and said ends of said can body 33' are flanged outwardly by the flanging grooves 68 and 72. Reciprocating motion is imparted to the die 69 by means of a sliding rod 73, by which said die is carried, said rod being suitably supported in a bracket 74, and having its outer end connected at 75, Figs. 1 and 2 of the drawings, with a lever 76, said lever being fulcrumed at 77, and carrying a roller 78 adapted to follow a groove cam 79 carried by the end of the rotating shaft 14. It is to be understood that the movement of the flanging die 69 is so timed with relation to the movement of the turret 10, that each can body is flanged at the position D, Fig. 3 of the drawings.

At the position E the reformed and flanged can body is ejected from the mandrel 12, into any suitable place of deposit not shown in the drawings, by an ejector finger 80, Figs. 1, 2 and 3 of the drawings, carried upon the end of a slidably mounted rod 81, said rod passing through the hollow turret shaft 8, and being operated by means of a

link 82, Figs. 1 and 2, a lever 83, fulcrumed at 84, and having its lower end connected at 85, with rod 86, extending under the machine to the lever 38, and pivotally connected therewith at 87.

70

To enable the ejector finger 80 to pass behind the inner flanged end of the can body to engage the same for the purpose of ejecting it from the mandrel, said can body must be initially moved upon said mandrel, to free the inner flanged end from the flanging groove 68. For this purpose a stationary cam member 88, Figs. 1, 3, and 5 of the drawings, is provided, said cam member being mounted upon a bracket 89 extending upwardly from the base 1, and positioned to engage the outer end flange of the can body 33' and by so doing to start the same slightly upon its mandrel, as said can body is carried by said mandrel from the position D to the position E, as shown in Fig. 3.

75

This initial ejecting movement of the can body is sufficient to free the inner end of said can body from the enlarged portion 66 of the mandrel 12, so that said can body is loose upon said mandrel, and can be easily engaged and removed by the ejector finger 80.

80

The operation of the machine may be briefly summarized as follows: A supply of flattened can bodies 32 is placed in the magazine 30^a, the lowermost can body 33 resting upon the pusher fingers 45. Upon the withdrawal and subsequent return movement of the slide 35, said lowermost flattened can body 33 is removed from the bottom of the magazine 30^a by said pusher fingers, and positioned upon the guide members 46. Said can body is then engaged by the notches 49 of the swinging arms 47 and is compressed laterally thereby. The spreader rods 62 and the spreader horn 63 are then introduced into said can body to further spread or open the same, after which, upon the next inward movement of the slide 35, the can body is forced onto the positioned mandrel 12. The intermittent rotation of the turret 10 carries the mandrel 12, with the partially reformed can body 33' thereon, to the position C of Fig. 3 of the drawings. In this position the ironing roller 20, revolving in contact with the can body 33', restores the same to its original cylindrical form. The reformed can body is then carried to the position D where end flanges are formed thereon by action of the flanging die 69 as hereinbefore described.

95

The next movement of the turret 10 carries the reformed and flanged can body to the position E, where said can body is removed from the mandrel by the ejector finger 80.

100

The various interworking parts of the machine are so timed as to act successively upon can bodies positioned upon each of the

105

110

115

120

125

130

mandrels 12, carried by the turret 10. Thus as each of said mandrels 12 passes the position A, Fig. 3 of the drawings, a flattened can body is partially spread and pushed thereupon, and each can body is reformed at the position C, flanged at the position D, and ejected at the position E, as its mandrel is successively carried to said positions.

The invention has hereinbefore been described and is herewith illustrated in its preferred form. It is to be understood however, that variations may be made in the construction and arrangement of the working parts of the machine without altering, or in any way affecting the principles of the invention. I, therefore, do not wish to be construed as limiting the invention in this respect, but on the contrary, I desire to be understood as claiming the invention as broadly as the state of the prior art will permit.

Having thus described the invention, what is claimed as new and desired to be protected by Letters Patent, is—

1. In a machine for the described purpose, the combination with means for receiving and holding a deformed can body, of means for expanding the same and causing it to be applied endwise to said receiving and holding means, means associated therewith for engaging with the surface of said can body for restoring the same into substantially cylindrical form, and edge-curling means for flanging the ends of said restored can body.

2. In a machine for the described purpose, the combination with a mandrel for receiving can bodies in a deformed condition, of means for expanding the same and causing them to be applied endwise to said mandrel, means associated therewith for engaging with the surface of said can body for reforming the same into substantially cylindrical condition, and edge-curling means for forming a flange upon an end of said reformed can body.

3. In a machine for the described purpose, the combination with a rotatable mandrel for receiving a can body in a deformed condition, of means for expanding it and causing it to be applied endwise to said mandrel, means associated therewith for engaging with the surface of said can body for the ironing thereof into substantially cylindrical form, and means for forming a flange upon an end of said can body.

4. In a machine for the described purpose the combination with a mandrel for receiving deformed can bodies, of means for initially opening the deformed can bodies and applying the same onto said mandrel, means associated with said mandrel for restoring the can body thereon to substantially cylindrical form, and means for flanging the ends of said can body.

5. In a machine for the described purpose, the combination with a mandrel for receiving open ended deformed can bodies, of means for feeding said can bodies endwise onto said mandrel, means for expanding the can bodies, means for engaging with the surface of the deformed can body thereon for the ironing thereof, to restore the same to original form, and means for outwardly flanging the edges of both of the open ends of the reformed can body positioned upon said mandrel.

6. In a machine for the described purpose, the combination with a cylindrical mandrel for receiving deformed can bodies, of a holder for said can bodies, devices for successively removing said can bodies from said holder and applying the same onto said mandrel, means associated with said mandrel for engaging with the surface of the deformed can body thereon for the ironing thereof to restore the same to original form, and means for flanging the ends of the reformed can body positioned upon said mandrel.

7. In a machine for the described purpose, the combination with a series of mandrels, of an ironing roller associated with said mandrels, devices for feeding deformed can bodies successively onto said mandrels, means for successively placing the mandrels within the sphere of action of said ironing roller, for reforming the can bodies upon said mandrels, and means for successively forming flanges upon the ends of said reformed can bodies positioned upon said mandrels.

8. In a machine for the described purpose, the combination with a mandrel for receiving deformed can bodies, of means for delivering deformed can bodies onto said mandrel, means associated with said mandrel for engaging with the surface of a deformed can body thereon for the ironing thereof to restore the same to normal condition, a curling die arranged around the mandrel for forming a flange upon an end of the reformed can body on said mandrel, and means associated with said mandrel for ejecting therefrom the reformed and flanged can body.

9. In a machine for the described purpose, the combination with means for receiving and holding deformed can bodies, of means for expanding deformed can bodies and causing the same to be applied endwise to said receiving and holding means, means for engaging with the surface of said can bodies for restoring the same to normal condition, and reciprocating devices for outwardly curling and forming a flange upon an end of the reformed can body.

10. In a machine for the described purpose, the combination of a tapered man-

- 5 mandrel adapted to expand a deformed can body when the latter is applied endwise over said mandrel, means for restoring said can body to normal form, reciprocating devices for outwardly curling and forming a flange upon an end of the can body after it has been expanded and reformed, and means for ejecting the reformed and flanged can body from said mandrel.
- 10 11. In a machine for the described purpose, the combination with a rotatable mandrel for receiving a deformed can body, of means associated with said mandrel for engaging with the surface of a can body thereon, for the ironing thereof, to restore the same to original form, reciprocating means for flanging the ends of said reformed can body, and means for ejecting the reformed and flanged can body from said mandrel.
- 15 12. In a machine for the described purpose, the combination with a freely rotatable mandrel for receiving a deformed can body, of rotating means for engaging with the surface of said can body to restore the same to original form, horizontally reciprocating devices, co-acting with said mandrel for flanging the ends of the reformed can body thereon, and means for automatically removing the reformed and flanged can body from said mandrel.
- 20 13. In a machine for the described purpose, the combination with means for receiving deformed can bodies and partly reforming the same, of a mandrel for receiving and holding said partly reformed can bodies, devices for expanding and positioning endwise said partly reformed can bodies successively upon the mandrel, means co-acting with said mandrel for restoring the can body thereon to original form, means for flanging the ends of the reformed can body upon said mandrel, and means for removing the reformed and flanged can body from the mandrel.
- 25 14. In a machine for the described purpose, a holder adapted to contain a stack of deformed can bodies, a movable series of mandrels for receiving and holding deformed can bodies, devices associated with said holder for partly reforming the deformed can bodies and delivering the same successively onto said mandrels, means co-acting with the mandrels for restoring the partly reformed can bodies thereon to original form, devices for flanging the ends of the reformed can bodies, and mechanism for positioning the mandrels successively with respect to said delivery means, said reforming means and said flanging means.
- 30 15. In a machine for the described purpose, a mandrel for receiving and holding a deformed can body, means for expanding a deformed can body and causing the same to be applied endwise on to said mandrel, means for restoring said can body to its
- original form, and a reciprocating flanging die movable relative to and adapted to co-act with said mandrel for flanging the ends of the reformed can body thereon.
- 35 16. In a machine for the described purpose, a mandrel for receiving and holding a deformed can body, means for reforming said can body, a horizontally reciprocating flanging die adapted to co-act with said mandrel for flanging the ends of the can body thereon, means for applying the deformed can body onto said mandrel, means for removing the reformed and flanged can body from said mandrel, and mechanism for moving said mandrel to carry said can body successively from said applying means to said reforming means, said flanging die, and said removing means.
- 40 17. In an apparatus for the described purpose, a mandrel for receiving and holding a deformed can body, means for expanding a deformed can body and causing the same to be applied endwise on to said mandrel, means for reforming said can body, a horizontally reciprocating flanging die movable relative to the mandrel for flanging the ends of the reformed can body, and mechanism for positioning said mandrel with the reformed can body thereon in axial alignment with said flanging die.
- 45 18. In an apparatus for the described purpose, a rotatable turret, a freely rotatable mandrel carried thereby, means for feeding a deformed can body onto said mandrel, means for reforming said can body, devices coacting with said mandrel for flanging the ends of the reformed can body carried thereby, and mechanism for rotating said turret to carry said mandrel successively from said applying means to said reforming means and said flanging means.
- 50 19. In an apparatus for the described purpose, a holder adapted to contain a supply of deformed can bodies, a rotatable turret positioned in proximity to said holder, a mandrel carried by said turret, means for removing a can body from said holder and positioning the same upon said mandrel, means for reforming the can body thereon, a reciprocating flanging die for flanging the ends of the reformed can body positioned upon said mandrel, means associated with said turret for ejecting the reformed and flanged can body from said mandrel, mechanism for intermittently rotating said turret to carry said mandrel into and out of operative relation with said applying means, said flanging die and said ejecting means, and devices for operating said means and said die in timed relation to the movements of said turret.
- 55 20. In an apparatus for the described purpose, a freely rotatable mandrel having its diameter enlarged near one end thereof, an annular shoulder upon said mandrel ad-

- 6
1. Jacent to said portion of enlarged diameter, said shoulder having an annular groove formed in the face thereof, means for positioning a deformed can body upon said mandrel, means for reforming said can body, a flanging die positioned in axial alignment with said mandrel and adapted to co-act therewith to force the end of the reformed can body thereon over said portion of enlarged diameter and into the groove of said shoulder, means for partially removing the flanged can body from said mandrel to free the flanged end thereof from said portion of enlarged diameter, and devices for engaging said can body and removing the same from said mandrel.
2. In an apparatus for the described purpose, a mandrel adapted to receive and hold a deformed can body, means for expanding a deformed can body and causing the same to be applied endwise on to said mandrel, means for reforming said can body, an annular flanging die adapted to be passed over the end of said mandrel and to engage the end of said can body for the purpose of flanging the same, and mechanism for moving said mandrel into and out of the sphere of action of said flanging die.
3. In a machine for the described purpose, devices for receiving and holding a flattened unflanged can body, means co-acting therewith for expanding and restoring the can body to original form, and associated devices for flanging the ends of the reformed can body.
4. In a machine for the described purpose, the combination with means for receiving a flattened unflanged can body, and means for expanding and restoring the same to original form, of mechanism associated therewith for flanging an end of the reformed can body.
5. In a machine for the described purpose, the combination with means for receiving a flattened unflanged can body and restoring the same to original form, of mechanism for flanging an end of the reformed can body, and means for placing the reformed can body within the sphere of the flanging mechanism.
6. In a machine for the described purpose, the combination with means for receiving a flattened unflanged can body and restoring the same to original form, of associated instrumentalities for flanging an end of the reformed can body, and devices for ejecting the flanged body.
7. In a machine for the described purpose, the combination with a mandrel for receiving deformed can bodies, of means co-acting therewith for reforming the body on said mandrel to original form, associated means for flanging an end of the reformed can body while on said mandrel, and means for moving the mandrel to place the reformed can body within the sphere of the flanging means.
8. In a machine for the described purpose, the combination with means for receiving a deformed can body and outwardly expanding, inwardly compressing and ironing devices for restoring the same to original form, of flanging mechanism associated therewith for flanging the ends of the reformed can body.
9. In a machine for the described purpose, the combination with a mandrel adapted to receive and hold a deformed can body, of means co-acting therewith for reforming said can body to original form, flanging mechanism for flanging the ends of the reformed can body, means for moving the mandrel with the reformed can body thereon into and out of the sphere of the flanging mechanism, and devices for ejecting the flanged can from the said mandrel.
10. In a machine for the described purpose, the combination with a mandrel provided with an inner flanging portion, of devices for placing a deformed can body onto said mandrel, means co-acting therewith for reforming the can body to original form, a flanging die for acting against one end of the reformed can body to force the opposing end thereof onto the flanging portion of the mandrel to flange the inner end of the body while the said die flanges the outer end thereof, means for moving the mandrel into and out of the sphere of the flanging die, and devices for ejecting the flanged can body from the said mandrel.
11. In a machine for the described purpose, the combination with a mandrel provided with an inner flanging portion, of devices for placing a deformed can body onto said mandrel, means co-acting with said mandrel to reform the can body to original form, means for forcing the inner end of the reformed can body onto the flanging portion of the mandrel for flanging said end of the body, and devices for ejecting the reformed flanged can body.
12. In a machine for the described purpose, a mandrel provided with an enlarged inner flanging portion, devices for placing a deformed can body on said mandrel, means co-acting with said mandrel for restoring the deformed can body to original form, flanging means associated with said mandrel for forcing the reformed can body onto the flanging portions of the mandrel to flange the inner end of the can body while acting to flange the outer end thereof and mechanism for moving the mandrel in and out of the sphere of the flanging means.
13. In a machine for reforming can bodies, the combination of internally acting expanding means, devices for compressing the body at its greatest diameter to further expand the same, means for ironing the body

circumferentially to smooth the same to cylindrical form, and means for forming the straight ends of the body into seaming flanges.

5 33. In a machine for reforming flattened unflanged can bodies, in combination: internally acting expanding devices, means for compressing the can body externally at its greatest diameter, and means for forming 10 straight ends of the body into seaming flanges.

34. In a machine for reforming flattened unflanged can bodies, in combination: internally acting expanding devices, means for compressing the can body externally at its greatest diameter, means for ironing the expanded body to cylindrical form, and means for forming the end edges of the ironed body into seaming flanges.

20 35. In a machine for reforming flattened unflanged can bodies, in combination: internally acting expanding devices, means for compressing the can body externally at its greatest diameter, means for ironing the expanded body to cylindrical form, and means for forming a seaming flange on said body.

36. In a machine for reforming can bodies, in combination: means for expanding the 30 can body from end to end; means for further changing the expanded can body to cylindrical form; and means for forming a seaming flange on said body.

37. The combination of a mandrel, a 35 flange-forming die at one end of the mandrel, a flange-forming die adapted to en-

circle the mandrel, and means for changing the distance between said dies to flange a can body on said mandrel.

38. The combination of a mandrel, means for expanding a deformed can body and causing the same to be applied endwise on to said mandrel, means for reducing a deformed and open-ended can body to cylindrical form while on said mandrel, co-operating dies for engaging the edges of the can body while on said mandrel, one of said dies having means for forming a seaming flange on said can body, and means for causing said dies to exert pressure on said can body in a direction longitudinal of the mandrel.

39. The combination of a mandrel, means for reducing a deformed and open-ended can body to cylindrical form while on said mandrel, co-operating dies for engaging the edges of the can body while on said mandrel, one of said dies having means for forming a seaming flange on said can body, and means for causing said dies to exert pressure 60 on said can body in a direction longitudinal of the mandrel, one of said dies having a shoulder concentric with the mandrel and adapted to enter between the mandrel and the can body.

In testimony whereof I have signed my name to this specification in the presence of two subscribing witnesses.

JAMES A. GRAY.
